UNITED STATES PATENT OFFICE.

JAMES M. COLVEN, OF OSSINING, NEW YORK.

FILTER.

1,125,899.

Specification of Letters Patent.

Patented Jan. 19, 1915.

Application filed May 7, 1914. Serial No. 836,881.

To all whom it may concern:

Be it known that I, JAMES M. COLVEN, a citizen of the United States, and a resident of Ossining, in the county of Westchester and State of New York, have invented certain new and useful Improvements in Filters, of which the following is a specification.

My invention relates to the type of self-cleaning filter set forth in my Letters Patent No. 1,099,286, dated June 9th, 1914, designed for the purification of water and other liquids, in which the flow of liquid is reversed through the filtering medium,—the filter being designed primarily for attachment to a faucet or other source of liquid supply, as when used for the purification of water for domestic purposes, for the supplying of drinking water, and for affording clear, uncontaminated water or liquid for use in the various arts and manufactures.

The object of both inventions is the production of a simple, compact, and effective reversible filter of the character designated, of moderate cost, controlled by a single conical valve plug, only one end of which (that to which the handle is attached) protrudes through the casing, which latter is adapted to receive and support an integral filter cartridge which may be readily inserted, removed and duplicated when expedient. A distinctive feature of my Letters Patent hereinbefore referred to is the provision of an axial discharge duct in the reversing plug in conjunction with a circuitous discharge passage in the casing, whereby the construction and operation of the filter as a whole is simplified and rendered effective. But this axial discharge duct in the reversing plug renders the finishing of the plug difficult and expensive because it is not adapted for convenient centralization in the finishing lathe; and it is the main object of my present invention to obviate this difficulty without impairing the practical merits of the plug or filter as attained by said prior invention.

Hence the present invention consists in the specific construction of the plug itself, the rest of the filter being the same in construction and operation as in my said Letters Patent, and the distinctive feature in the present case being the formation of the plug with a continuous, solid axial center, and with longitudinal peripheral ports which perform the same function as the

aforesaid axial port, as hereinafter more fully set forth. By this construction the plug may be quickly, conveniently and accurately centralized in the finishing lathe. Furthermore, obviously, in the casting of the plug the central core is dispensed with, which is a further advantage in manufacture, reducing the plug cores from three to two, and these latter peripheral, and requiring no special skill or accuracy.

In the accompanying drawings, Figure 1, is what may be designated as a front elevation of my improved self-cleaning filter; Fig. 2, a rear elevation; Fig. 3, a right hand side elevation; and Fig. 4, a left hand side elevation; Fig. 5, is a central vertical section of the filter, full size, taken upon plane of line 5—5 Fig. 2; Fig. 6, a sectional elevation taken upon plane of line 6—6 Fig. 5; Fig. 7, a sectional detail showing means for restricting the axial movement of the reversing plug. Fig. 8, is a detail elevation of the reversing plug in part showing its longitudinal peripheral discharge passages.

The barrel or casing C, is formed with the internally threaded nipple c, for attachment to a water faucet or other source of liquid supply, and with an inlet c', and lateral circuitous discharge conduit c², leading to the outlet c³. Interposed between the inlet c', and the discharge conduit c², is the conical plug P, formed with the peripheral longitudinal discharge passages p', p², which are in constant end communication with said circuitous discharge conduit c², (as shown in the case of passage p², in Fig. 6,) said plug P, being also formed with port p³, communicating with the inlet c', as shown more particularly in Fig. 5,—said peripheral port p³, being approximately semi-circular in extent so as to communicate with either of the internal ports c⁴, c⁵, formed in the casing C, as shown particularly in Fig. 5. These internal ports c⁴, c⁵, communicate with the spaces in the casing C, on either side of the filter cartridge F, when the latter is positioned in said casing as shown in Fig. 5. The filter cartridge F, is cylindrical in form, its closed ends being perforated or intersticed for the passage of the liquid to be filtered, and it is filled or charged with any suitable filtering medium, as sand, charcoal, &c., preferably with a central disk f, of relatively close porous material practically dividing the filter into compartments and acting as an effectual barrier to the passage

through the filter of the foreign matter which it is sought to eliminate from the liquid.

The filter cylinder F, is formed with an annular flange f', which is threaded peripherally to engage with the female thread c⁶, tapped in the body of the casing, which female thread c⁶, not only affords means for positioning the filter cylinder F, but also for the attachment of the closure cap C', as shown in Fig. 5. The flange f', of the filter cylinder F, is formed with the annular shoulder f², between which and the seat c⁵, of the casing is interposed a gasket g, which prevents the passage of liquid from one side of the casing to the other except only through the filter F. Gaskets are also interposed between the outer flange c'', of the cap C', and the opposed surfaces of the casing as shown in Fig. 5, to insure against leakage.

The conical portion of the reversing plug P, is accurately ground to a water-tight fit with its seat in the casing C, and is of such length that its shoulder p⁴, extends slightly beyond the annular packing shoulder c⁸, formed in the casing for the reception of the gasket g',—said gasket resting upon both said shoulders p⁴, and c⁸, and being interposed between them and the inner surface of the tightening nut n, which fits over the cylindrical portion p^x of the reversing plug P, and is formed with a peripheral thread n', for engagement with the female thread c⁶, in the casing. I thus afford ready and convenient means whereby wear between the reversing plug and its seat may be taken up and compensated for, at the same time insuring a fluid tight joint at the protruding end of the plug, which may be provided with the usual handle h, or other means whereby it may be partially rotated on its axis, the extent of such motion being limited by a stop c¹⁰, on the casing arranged for engagement with shoulders p⁵, p⁶, on the plug, as indicated in Figs. 6, and 7, or by resort to any other well known mechanical expedient.

In operation when the parts are in the position shown in Fig. 5, (the stop c¹⁰, being in contact with the shoulder p⁵), the flow of liquid will be through the inlet c', peripheral port p³, and internal port c⁵, to and through the filter F, to the internal port c⁴,

and through the peripheral port p', to the circuitous conduit c², to be discharged through the outlet c³. By reversing the handle h, until the stop c¹⁰, contacts with the shoulder p⁶, the liquid will flow through the inlet c', peripheral port p³, internal port c⁴, filter F, internal port c¹, and peripheral port p², to the circuitous conduit c², and thence through the outlet c³. Thus a simple motion, a partial turn of the conical plug from one stop contact to the other, will suffice to reverse the flow of the liquid and wash out and eliminate from the filter any foreign matter that may have accumulated therein through use; and this reversal may be instantly effected whenever and as often as may be found expedient.

It will be seen that the peripheral discharge passages p', p², are an important factor in my present construction and arrangement of parts, enabling me to greatly simplify, and cheapen the device. At the same time I dispense with one end packing for the plug,—the handle end thereof alone projecting through the casing.

What I claim as my invention and desire to secure by Letters Patent is,

A filter of the character designated, comprising a casing adapted for connection with a source of liquid supply, a filter cartridge mounted in said casing and dividing it into two compartments, said casing being formed with ports communicating respectively with said compartments, a valve plug seated in said casing and interposed between said casing ports and the inlet, and formed with longitudinal peripheral discharge ports communicating alternately with the casing ports, said plug being also formed with a transverse peripheral port communicating with the inlet, and alternating with the casing ports, said casing being also formed with a circuitous discharge passage connecting said peripheral discharge passages in the plug permanently with the outlet, whereby the flow of liquid through the filter cartridge may be reversed and the discharge of liquid maintained through either of said peripheral discharge passages in the plug, for the purpose described.

JAMES M. COLVEN.
